Attorney, Agent, or Firm—Barnes & Thornburg***[57] CLAIM**

The ornamental design for a systems controller for an air mattress, as shown and described.

DESCRIPTION

FIG. 1 is a perspective view of the front and right side of systems controller for an air mattress showing my new design;

FIG. 2 is a front view of the systems controller for an air mattress of FIG. 1;

FIG. 3 is a left side view of the systems controller for an air mattress of FIG. 2;

FIG. 4 is a right side view of the systems controller for an air mattress of FIG. 2;

FIG. 5 is a bottom view of the systems controller for an air mattress of FIG. 2;

FIG. 6 is a top view of the systems controller for an air mattress of FIG. 2 thereof; and,

FIG. 7 is a back view of the systems controller for an air mattress of FIG. 2.

The broken line showing of a dial and gauge, in FIG. 1, is for illustrative purposes only and forms no part of the claimed design.
